CLAIM

The ornamental design for a day and date clock, as shown and described.

DESCRIPTION

FIG. 1 is a front perspective view of a day and date clock showing my new design;

FIG. 2 is a front view thereof;

FIG. 3 left side view thereof;

FIG. 4 is a right side view thereof;

FIG. 5 is a top view thereof; and,

FIG. 6 is a bottom view thereof.

The broken lines are for illustrative purposes only and forms no part of the claimed design.
